(57) **CLAIM**

The ornamental design for a punching-free curtain, as shown and described.

DESCRIPTION

FIG. 1 is a front, top perspective view of a punching-free curtain, showing my new design;
FIG. 2 is a rear, bottom perspective view thereof;
FIG. 3 is a front elevation view thereof;
FIG. 4 is a rear elevation view thereof;
FIG. 5 is an enlarged left side elevation view thereof;
FIG. 6 is an enlarged right side elevation view thereof;
FIG. 7 is a top plan view thereof;
FIG. 8 is a bottom plan view thereof; and,
FIG. 9 is an enlarged view of detail "9" identified in FIG. 1. The dashed broken lines in the figures illustrate portions of the punching-free curtain that form no part of the claimed design. The dash-dot-dash broken lines in FIGS. 1 and 9 depict the bounds of the enlarged views and form no part of the claimed design.
